[57] CLAIM

The ornamental design for a floor sign, as shown and described.

DESCRIPTION

FIG. 1 is a front perspective view of a floor sign showing our new design;

FIG. 2 is a front elevational view thereof;

FIG. 3 is a rear perspective view thereof, and,

FIG. 4 is a side elevational view thereof, as viewed from the right in FIG. 3, with the opposite side being a mirror image of that shown in FIG. 4.

The broken line showing in FIG. 1 forms no part of the present design, and is intended only to designate that portion of the floor sign to which indicia may be applied.
